UNITED STATES PATENT OFFICE.

FRANK J. FOSTER AND HUGO WAHREN, OF HAWLEY, PENNSYLVANIA

BOX-LID HOLDER.

Application filed February 11, 1927. Serial No. 167,531.

This invention relates to holders primarily adapted for supporting the lids of cigar boxes in elevated positions to display the contents thereof and to permit humidifying.

Another object of the invention comprehends the supporting of the lid upon the back of the box to effectively display the particular trade-name of the commodity.

With the above and other objects in view, the invention further consists of the following novel features and details of construction, to be hereinafter more fully described, illustrated in the accompanying drawings, and pointed out in the appended claim.

In the drawing:—

Figure 1 is a perspective of a cigar box partly broken away to illustrate the application of the invention.

Figure 2 is a vertical sectional view taken through a portion of the lid and back of the box illustrating the disposition of the invention.

Figure 3 is a fragmentary rear elevation of the box lid and holder.

Figures 4 and 5 are perspectives of the invention per se.

Referring to the drawing in detail, wherein like characters of reference denote corresponding parts, the reference character 10 indicates a box or container within which commodities are packed and in this instance the box is of the form generally used in the packing of cigars. As generally known, the lids 11 of boxes of the character described are hingedly mounted upon the backs thereof by an adhesive strip. In the application of the invention said strip is severed to segregate the box and lid.

In carrying out our invention we provide resilient strips 12 provided with substantially inverted U-shaped loops 13 having the extremities thereof sprung inwardly toward said strips, substantially as illustrated in Figure 2 of the drawing. Said loops are adapted to receive the upper edges of the box back. The remaining ends of the strips provide substantially elongated U-shaped loops 14 disposed upon the opposed sides of the strips with respect to the loops 13. The loops 14 are curvilinear as indicated at 15 to provide a gripping surface for appreciable portions of their lengths. Said loops 14 are adapted to receive the lower edges

of the lid 11 in the manner as illustrated in Figures 1, 2 and 3. In such position the 55 trade-name, name of the manufacturer etc., as stamped or otherwise provided upon the inner side of the lid is exposed for display. The disposition of the lid will not only offer convenient means for displaying the 60 particular commodity but in the instance of cigars the same may be more effectively humidified.

The end of the loop 13 is beveled, as indicated at 13', and at such an angle that the 65 extremity may be rounded, as at 13''. The particular bevel end may be projected downwardly within the box and between the tapered or pointed ends of the cigars without causing injury thereto, and to provide a 70 better support or grip for the loop 13. Said end, by reason of its specific construction may be readily guided between the ends of the cigars when applying the holder upon the box.

The invention is susceptible of various changes in its form, proportions and minor details of construction, and the right is herein reserved to make such changes as properly fall within the scope of the appended 80 claim.

Having thus described the invention, what is claimed is:—

A holder for use upon cigar boxes to support the lid therefor in a perpendicular 85 position to the box back to effectively display the trade-name of a cigar comprising a resilient strip, the lowermost end of the strip being curved upon itself to provide an upstanding U-shaped loop sprung inwardly 90 toward the larger portion of the strip to toward the larger portion of the strip to frictionally engage the lower edge of the lid, the uppermost end of the strip being 95 reversely arranged and disposed in staggered relation to that of the first mentioned loop and which is adapted to receive the upper edge of the box back, and the extremity of the uppermost hook being beveled and rounded to prevent injury to the contents of the box when extended between the tapered ends of the cigars.

In testimony whereof we affix our signatures.

FRANK J. FOSTER.
HUGO WAHREN.
